(57) **CLAIM**

The ornamental design for a digital side display extension, as shown and described.

DESCRIPTION

FIG. 1 is a forward view into an aircraft cockpit showing our new design of a left and right digital side display extension; FIG. 2 is a perspective view showing the left digital side display extension of FIG. 1;

FIG. 3 is a perspective view showing the right digital side display extension of FIG. 1;

FIG. 4 is a front view of the digital side display extension of FIG. 2; and,

FIG. 5 is a front view of the digital side display extension of FIG. 3.

In FIGS. 1–5, broken lines indicate environmental structure that forms no part of the claimed design.
